US0D1025549S

(12) United States Design Patent (10) Patent No.: US D1,025,549 S
(45) Date of Patent: * May 7, 2024

(54) SWEATER

(71) Applicant: Kitanica, LLC, Oakland, CA (US)

(72) Inventor: Leonard Riccio, Oakland, CA (US)

() Term: 15 Years

(21) Appl. No.: 29/776,081

(22) Filed: Mar. 26, 2021

(51) LOC (14) Cl. 02-02

(52) U.S. Cl.

USPC D2/750

(58) Field of Classification Search

USPC D2/749-750, 840, 844, 853

CPC A41B 1/00; A41D 1/00; A41D 1/18
